CARL H. EHLERS, OF PENFIELD, PENNSYLVANIA, ASSIGNOR TO THE ATLANTIC REFINING COMPANY, OF PHILADELPHIA, PENNSYLVANIA, A CORPORATION OF PENNSYLVANIA

CLOSURE APPARATUS

Application filed August 10, 1925. Serial No. 49,477.

My invention relates to apparatus utilizable for preventing back flow of a fluid from a storage tank, container, or other structure.

In accordance with my invention, a conduit 5 communicating with a tank, container, or other structure, as aforesaid, is closed or sealed in a plurality of regions, and more particularly, the closing or sealing mechanism comprises a valve disk biased into engagement with a suitable seat by a coiled spring, or equivalent.

Further in accordance with my invention, in a system dispensing liquid under pressure, a filling, gauging, or other conduit is closed 15 or sealed by a suitable structure, as a cork ball, moved into engagement with its seat by the liquid as it rises in response to the applied pressure.

My invention resides in apparatus of the 20 character hereinafter described and claimed.

For an illustration of one of the various forms my invention may take, reference is to be had to the accompanying drawing, in which:

25 Fig. 1 is a vertical sectional view of apparatus constructed in accordance with my invention.

Fig. 2 is a sectional view taken on the line 2—2 of Fig. 1, looking in the direction of the 30 arrows.

Referring to the drawing, there is illustrated a conduit 1, utilizable as hereinafter described, formed by a casing 2 secured in desired manner at one end to a tank or receptacle and at its other end to an upper casing. Preferably, however, one end of casing 2 is provided with a flange 3, and the other end with a corresponding flange 3a, resting on and secured to a similar flange 4 carried by a pipe 5, or equivalent, leading to a tank or receptacle (not shown). Flanges 3 and 4 are suitably secured together, as by the bolts 6 and nuts 7, and to ensure a fluid-tight connection a washer 8, of suitable material, not affected by the contents of the tank, may be disposed between said flanges. If oil, or a similar substance, is contained in the tank, it is desirable that the washer be 45 formed of a material not affected thereby, as

a composition of asbestos, and suitable binding material.

The casing 2 is provided with an offset box 9, at times receiving a ball 10, preferably formed of cork. It is to be understood, however, that ball 10 may be constructed of other materials, as a thin casing of suitable metal entrapping a body of gas, as air. Ball 10 at times is caused to travel from the offset portion 9 to a position adjacent the top of conduit 1. To the end that such movement of the ball may be expeditiously effected, guiding ribs or tracks 11, formed preferably integrally with the casing 2, extend laterally into the conduit 1.

An upper conduit 12 aligned with conduit 1 is formed by an upper casing 13 having a flange 14 resting upon and suitably secured to flange 3 of casing 2, as by bolts 15, each held in position by a nut 16. To ensure a 70 fluid-tight connection at this point, a washer 17, of material corresponding to that of washer 8, is disposed between the flanges 3 and 14.

An annular seat 18 is provided on the interior surface of casing 13 in a region where its internal diameter is somewhat less than that of the ball 10, and at a suitable distance thereabove, an outwardly extending flanged portion 19 of the upper casing forms a second 75 annular seat 20. The upper wall 21 of casing 13 is provided with a third annular seat 22 and a threaded portion 23, the latter extending from the top of said upper wall, preferably on the interior thereof, a suitable distance toward the flange 19.

A cap 24, having a projection 25 to be engaged by a wrench, or other suitable tool, comprises a sleeve 26 threaded exteriorly, as indicated at 27. An annular ledge 28 formed integrally with cap 24 carries a washer 29, of material corresponding to that of washer 8. A collar 30, likewise preferably formed integrally with cap 24, extends longitudinally toward the conduit 12 and is provided with 90 one or more diametrically extending screws 31, or equivalent, projecting a slight distance inwardly beyond the inner surface of the collar 30.

A valve disk 32 comprises an annular ledge 100

or plate 33 carrying a washer 34, of material corresponding to that of the washer 8. A sleeve 35, having an external diameter corresponding to the internal diameter of the collar 30, is received by said collar against the expansive force of a spiral spring 36. A circumferential groove 37 of considerable width, formed exteriorly on sleeve 35, receives the ends of screws 31 which engage the walls 10 of the groove to control the movement of sleeve 35 within the collar 30.

Apparatus of the character herein described is especially adapted for use in connection with systems dispensing oil or gasoline under air or hydraulic pressure, and, therefore, for purposes of illustration, it may be assumed that pipe 5 leads to a suitable tank about to be furnished with a fresh supply of such liquid. As a preliminary measure, the extraneous pressure is cut off, whereupon the cap 24 is removed from the upper wall 21 of casing 13 and a fill bushing substituted therefor. Under such circumstances, ball 10 will be in the position indicated by the 15 dot and dash line of Fig. 1, and the desired quantity of liquid may be introduced into the tank.

The fill bushing is now removed and cap 24 again placed in position on the upper wall 30 21. Immediately after initial engagement 21 of threaded sleeve 26 with the threads 27, washer 34 on the ledge 33 engages the seat 20, since upon removal of the cap the expansive tendency of spiral spring 36 moved valve 35 disk 32 outwardly the full amount permitted by screws 31, which are positioned on the collar 30 and co-operate with a wall of the groove 37 to control the amount of outward movement of the valve 32 so that the washer 34 will engage seat 20 in the manner specified. Continued inward movement of cap 24 serves 40 to move collar 30 with respect to sleeve 35, compressing spring 36 and thereby effecting a liquid-tight seal between the seat 20 and washer 34. It is to be noted that after valve disk 32 has been firmly seated on seat 20, continued rotation of cap 24 no longer rotates the valve disk, which remains stationary while collar 30 is being rotated and moved 50 axially toward the seat 20. It follows, therefore, that washer 34 is not subjected to the usual twisting action when being seated, and as a result, has a much longer life while the seal effected thereby is capable of withstanding high pressure. Finally, when cap 24 is screwed entirely into the upper wall 21 of the casing 13, another liquid-tight seal is effected between the seat 22 and washer 29. It shall be understood that when cap 24 occupies the position last noted, the liquid-tight seal between seat 20 and washer 34 is maintained irrespective of pressure conditions within the tank.

If, when hydraulic pressure is being utilized as the dispensing agent, the extraneous

source of pressure should be cut into service during a time that cap 24 is removed, or improperly positioned, or if with said cap properly positioned a leak should have developed in the cap washers, the liquid within the 70 tank when forced upwardly through pipe 5 and conduit 1 will carry ball 10 against its seat to thereby prevent escape of the liquid.

Although I have described my invention as 75 utilizable for sealing the filling spout of an oil or gasoline tank, it is obvious that my invention may be otherwise utilized. For example, it is customary to provide individual tanks with an opening receiving suitable apparatus for gauging the depth of liquid, and 80 an opening of this character may be readily sealed by apparatus constructed in accordance with my invention.

Further, it is to be understood that my invention is not limited to use with tanks in which oil or gasoline is dispensed under pressure, for it is obvious that apparatus of the character herein disclosed may be utilized when dispensing other liquids under pressure or for sealing a tank or receptacle opening containing any liquid when an extraneous 90 source of pressure is not utilized.

Further, it is to be understood that ball 10 alone may be utilized to effect a seal, or ball 10 may be utilized in combination with the usual 95 type of cap comprising but a single seat. Further, it is to be understood that cap 24 may be separately utilized without ball 10, particularly when air pressure is the medium forcing the liquid from the tank, for under 10 such circumstances liquid would not rise into casing 2.

What I claim is:

1. In apparatus for dispensing liquid under pressure, valve structure comprising a 10 conduit communicating with a liquid supply, a valve housing secured to said conduit and communicating therewith, liquid actuated valve means for closing said conduit in a region adjacent said housing, and additional 11 closure means for closing said housing in a plurality of regions spaced from each other.

2. In apparatus for dispensing liquid under pressure, combined valve and closure structure comprising a housing, a cap for closing the exterior region thereof, a resiliently mounted valve carried by said cap for closing said housing in a region spaced from said first region, and a conduit communicating with said housing and containing a liquid actuated valve for closing the passage between the conduit and said housing upon rise of liquid in said conduit.

3. Closure apparatus for a liquid dispensing system comprising an upper housing, a closure cap having members sealing off said housing in a plurality of regions, a lower housing communicating with said upper housing and detachably secured thereto, and auxiliary valve structure for closing the pas- 1

sage between said housings upon rise of liquid in said lower housing.

4. Closure apparatus for a system dispensing liquid under pressure, comprising an upper housing, a cap closing said housing in one region and a resiliently mounted valve carried thereby for closing said housing at a remote region, a lower housing communicating with said upper housing, and fluid actuated valve structure adapted to close the passage between said housings upon removal of the cap in said first housing.

5. In a liquid dispensing system, a supply conduit, a valve housing forming an extension thereof, a cap closing the end of said housing, a valve carried by said cap for closing said housing in a region spaced from said first closure, said cap being adapted to urge said valve into snug and tight engagement with its seat, and a liquid actuated valve disposed in said supply conduit for shutting off communication with said housing upon displacement of said cap and valve structure.

6. In apparatus for dispensing liquid under pressure, valve structure comprising a non-perforated conduit communicating with a liquid supply, said conduit provided at its outer portion with a closure cap and means for sealing said cap with respect to said conduit, and a valve member supported solely by said closure cap and resiliently biased into position to normally seal and close off said conduit at a region remote from said cap, said closure cap adapted to preclude escape of liquid from the conduit upon movement of said valve from its seat.
